CHARLES F. SPERY, OF CHICAGO, ILLINOIS.

RADIATOR CORE.

Application filed August 1, 1921. Serial No. 488,969.

To all whom it may concern:

Be it known that I, CHARLES F. SPERY, a citizen of the United States, residing at Chicago, in the county of Cook and State of Illinois, have invented new and useful Improvements in Radiator Cores, of which the following is a specification.

This invention has relation to radiators for watercooled internal combustion engines, such as are commonly used on self propelled vehicles.

The object of the present invention is the provision of a radiator core of simplicity, of inexpensive construction, and of great efficiency. More particularly my aim is to provide a series of members for mixing and deflecting the air which passes through the radiator core. To this end my invention consists in the combinations and constructions set forth in the following description and indicated in the annexed drawing, of which:

Fig. 1 illustrates, in front elevation, a portion of a radiator core embodying the invention,

Fig. 2 shows a frame unit, a number of which combine to form the structure of Fig. 1,

Fig. 3 is a side elevation of one of the members which combine to form the water channels of the structure,

Fig. 4 is a cross sectional view of one of the water channels,

Figs. 5 and 6 are views of one of the deflectors of the device, and

Fig. 7 is a cross sectional view taken substantially on a line A—A of Fig. 5, and

Fig. 8 shows a modified form of deflector.

The type of radiator herein considered is made with a series of vertically disposed water channels 1, each of which, when viewed in vertical cross section as shown in Fig. 4, presents a water passage of a corrugated contour. In order to obtain such water channels I have provided a series of frames comprising corrugated strips 2 and 3, and these strips are suitably combined, as by top and bottom lock seams 4 and 5. When two such frames are assembled side by side the water passage of Fig. 4 is produced, and it is noticed that the side 2 of one frame abuts the side 3 of the next following frame, and that the pair of abutting sides form the channel.

Fig. 3 discloses the face of the frame side 2, and it is to be noted that the shape is

the same as the frame side 3, but in reversed relation. The frame side is made from a strip of thin metal hexagonally corrugated, and it is noticed that the inner apices of the 60 corrugations, 2^a, are entirely flat, but that the inclined surfaces 2^b and the outer apices 2^c are provided with depressions, which depressions commence a short distance from the edges of the metal strip. The strip 3 is, as stated, similarly shaped in reverse relation, whereby the flat apex of one is placed opposite the depressed apex of the other, as indicated in Fig. 4, and the water passage is thereby provided, but it is also important to note that the hexagonal bands along the edges of both strips contact, as indicated by the dotted outline 6 in Fig. 4, and these bands are soldered together in order to provide a water tight water channel.

The structure just described is known to the art to provide a very efficient radiator core, of the type referred to, particularly in case means can be introduced whereby the air flowing through the radiator core can be 80 directed toward and thrown against the sides of the water channels. In order to obtain such result I have placed a deflecting member 7 within each frame 2, 3, as indicated in Fig. 1. This member is made from 85 a thin strip of sheet metal corresponding in width to the strips 2 and 3, and it is made with corresponding border bands of semi-hexagonal contour, whereby, when the core is assembled, its front and rear faces are 90 caused to present hexagonally cellular shapes, closely resembling a honey comb.

The deflector 7, see also Figs. 5, 6, 7, is made with a series of cone shaped protuberances 7^b, 7^c, which are arranged in 95 alternately reversed relation both lengthwise and crosswise of the strip, and rising from the opposite surfaces 7^a to a uniform height. As the semihexagonal bands 7^e, 7^f rise on both sides substantially to the same height 100 it is seen that very little of the original surface of the strip remains, and that practically the entire strip is uniformly protruded in opposite directions. This is important to note, because any lack of uniformity has a 105 tendency to distort the metal, making it much more difficult and expensive to roll the strip into the desired shape. Upon examining Fig. 8 it is noticed that octagonal pyramids 9^a, 9^b rise from the deflector surface in opposite directions, and that they are 110 similarly spaced. It is not very material

whether these protuberances are cone shaped or pyramidal so far as the operation of the device is concerned, but in both cases it is important to note the relation which the 5 protuberances take to the corrugated contour of the water channels. This relation is best shown in Fig. 1, and it is noticed that the apices of the cones project into the cavities of the adjacent water channel corrugations. 10 It remains to be explained wherein the hereinbefore described shapes and members co-operate to increase the efficiency of a structure of this character, and for this purpose reference is invited to Fig. 5. Let it 15 be assumed that the left side of this view, where the arrow appears, represent the front of the radiator, and that the vehicle, on which the radiator is mounted to operate, is in motion in forward direction. Relatively 20 speaking the air is caused to rush through the core from the front. It is now seen that the air which enters through the corrugations, such as the corrugation 10, immediately strikes a cone 7^b, whereby it is directed 25 upward and deflected sidewise and thrown against the adjacent channel side. It may be suggested that the air will also pass downward, and so it may, but as the air commences to absorb heat the moment it strikes 30 the core it is more likely to rise than to sink. The air passing the said cone 7^b is now free to rise diagonally upward through the depression 11 formed between two diagonal rows of cones, and to escape through the 35 semihexagonal passage 12. During this travel the air strikes the second and third cone, and in so doing it is thrown against the channel sides with great force a number of times, whereas, if only diagonal ribs were 40 provided, the air would strike only once and then pass through the diagonal passage of such ribbed member. And it is well known to those versed in the art that the more often the air can be made to strike the channel 45 sides, the more thorough is also the heat absorption.

There is another important feature in this construction. Careful tests have shown me that, where a deflector having diagonal ribs 50 and channels between such ribs are used, the air encounters too much friction and becomes choked, which of course is undesirable. In the structure of my invention, on the other hand, it is seen that the air entering through the passage 10 may strike both the top and bottom inclines of the first cone 7^b, that it then may pass rearward and strike the bottom and top inclines of the next following cones 13, 14, finally to strike the rear 60 cone 15 before escaping through the corrugation 16. In other words, the air is free to find its way in any direction it is inclined to flow, and as it rushes through the radiator core it is compelled to strike the inclined 65 sides of a plurality of cones, and thereby

to be thrown with force against the channel sides repeatedly. The more thoroughly the air becomes mixed, and the more often it is thrown against the sides of the water channels, the more efficient the radiator is found 70 to be, hence the importance of the hereinbefore described structure, in which are combined elements to produce these results in a very thorough manner.

It is necessary to provide means for temporarily retaining the parts of the core in alinement during the assembling operation, and prior to the usual soldering process. For this purpose I have placed elongated ribs 18, 19 on the flat apices 2^a of the channel members 2, and, of course, similar ribs in the members 3. The center row of cones 7^b of the deflector 7 engage the said ribs of the member 2, and the reversed cones 7^c engage in the same manner the ribs of the 80 member 3. In order to indicate this construction it is noticed that the deflector member at the extreme left of Fig. 1 is shown cut, substantially through the vertical center. It is common to extrude semicircular buttons for locating purposes in structures of this kind, but it is readily seen that the apex of a cone, in this structure, would not find a very secure position between such buttons. Another objection to the buttons, if placed 90 within the bands, is that they do not receive any of the solder used for combining and making the core watertight, and as the metal often is slightly torn in extruding said buttons, it follows that the radiator core will 100 leak at such point. The extrusion of the long rib of the present structure, on the other hand, may be done with safety because the rise of the rib from end to end can be long and gentle. It may be asked why 105 the metal does not tear transversely of the rib, and the answer is, that all sheet metal of the kind used for devices of this kind will stand much bending and stretching across the grain of the metal, but not much longitudinally. For these reasons the long locating ribs of my invention are of importance.

I claim:

1. In a radiator core, the combination 115 with vertically disposed water channels, semihexagonally corrugated, of a deflector mountable between each adjacent pair of water channels, said deflectors having cone shaped protuberances diagonally arranged 120 in alternate series in opposite directions and extending into the cavities of the water channel corrugations.

2. In a honey comb radiator core, the combination with a series of frames, each comprising two semihexagonally formed strips of thin metal assembled in spaced relation the adjacent frame sides combining to form water channels, of a deflector strip mountable within each frame and having semi- 130

hexagonal bands abutting the borders of the water channels for the purpose of completing the honey comb shape, each deflector provided with peaked protuberances disposed in opposite directions and arranged to extend into the semihexagonal grooves of the water channels.

3. In combination, a series of vertically disposed corrugated water channels, and a thin metal deflector mountable between each adjacent pair of water channels, said deflectors provided with cone shaped protuberances rising from its surface in opposite directions, there being provided in the opposed sides of each pair of water channels series of pairs of horizontally disposed ribs and so placed that the protuberances arranged along the vertical centerline of the deflectors lodge between each pair of ribs.
4. A deflector for a radiator core made from a strip of thin sheet metal along the edges of which are provided semihexagonal bands and having, between said bands, alternate series of peaked protuberances projected in opposite directions in such relation to the bands, that a peak rises directly inside each hexagonal cavity of each band.
5. In a radiator core of the type described,

the combination with corrugated water channels, of thin sheet metal deflectors mountable between each adjacent pair of water channels to complete a honey comb shape, there being, in a horizontal plane, a peaked protuberance rising directly inside each hexagonal cavity along each edge of a deflector, and a peaked protuberance rising in the opposite direction intermediate to two first named protuberances, the protuberances being arranged diagonally in opposed alternate series extending from a cavity of one edge to the second following cavity of the other edge.

6. In a radiator core, a series of semi-hexagonal water channels, a series of intermediate deflectors having semihexagonal edge bands combining with the water channel sides to form a honeycomb structure, said deflectors provided, between the said bands, with three rows of projecting cones alternately right and left, the middle row engaging ribs on the adjacent water channel projections, the outer two rows projecting into the adjacent water channel cavities.

In testimony whereof, I have hereunto affixed my signature.

CHAS. F. SPERY.
